MERCURY VAPOR LAMP

Aristodeme J. Cosmetto, New York, N. Y.

Application July 17, 1946, Serial No. 684,199

5 Claims. (Cl. 240—11.4)

1

This invention relates to holders for mercury vapor lamps and more particularly to a water cooling arrangement therefor.

It is an object of the present invention to provide a water-cooled holder arrangement for vapor lamps in which the water passages are so shaped and disposed as to minimize, as far as possible, abrupt changes in the cross-section of the water flow, and thereby to eliminate eddy currents and air bubbles that tend to form in the cooling water.

It is another object of the invention to provide a cooling arrangement for vapor lamps in which there are no fragile glass-to-metal seals.

It is still another object of the invention to provide a water-cooled vapor lamp arrangement which can be assembled or disassembled by the turning of a single clamping member and wherein upon removal of this member the parts are free to be extracted by a simple pulling operation.

It is still another object of the invention to provide a holder and cooling jacket for vapor lamps wherein the metallic parts at the dangerously high potentials are not exposed, and the current-carrying wires are hidden in and insulated by the rubber tubes conducting the water.

It is still another object of the invention to provide a water-cooled vapor lamp in which all the elements are concentric to a single axis, thereby facilitating the mounting procedure and eliminating distortion which arises when glass elements as is the case where the elements are not concentric with the light source.

It is still another object of the invention to provide a water-cooled vapor lamp in which the glass elements are so shaped that they readily can be produced with the high accuracy necessary to eliminate distortion.

According to the invention, there is provided a main holder piece having an enlarged recess into which the various parts of the lamp and the cooling arrangement are fitted and into which a single screw cap is tightened to secure all of the parts to the holder. Projecting centrally from the bottom of the recess and in communication with an inlet cooling fluid pipe, is a terminal lamp support of spider cross-section having its end formed to receive the contact terminal at one end of a vapor lamp. This spider shaped support serves as a conductor and cooling liquid passes upwardly between spider projections for delivery to a transparent and insulating sleeve and about the vapor lamp. At the end of the sleeve the path of the cooling liquid reverses and moves downwardly between the sleeve and an outside casing.

2

The liquid is received in an annular space near the bottom of the recess and conducted away from the holder through a discharge tube. The contact terminal or clip for the outer end of the vapor lamp is seated in rubber in the outer end of the outer glass casing. The rubber cushion serves as a support and centering device for the tube. Both the inner sleeve and the casing at their inner ends are seated in rubber. Conducting wires are connected to the cooling fluid pipes which serve to feed current to the vapor lamp. A wire connection is made through the outer casing from the terminal of the vapor lamp at its outer end to the outlet cooling fluid tube or pipe. Preferably the holder is made of plastic material but reinforced with metal parts where wear surfaces are needed.

For other objects and for a better understanding of the invention, reference may be had to the following detailed description taken in connection with the accompanying drawing, in which

Fig. 1 is a cross-sectional view, in elevation, of the holder with the lamp secured in place therein;

Fig. 2 is a cross-sectional view showing a continuation of the lower end of the lamp shown in Fig. 1 and illustrating the connection of the expandable conducting wires within the cooling fluid tubes.

Fig. 3 is a detailed view of the vertical support for the lamp;

Fig. 4 is an enlarged cross-sectional view of the support taken on the line 4—4 of Fig. 3;

Fig. 5 is a top plan view of a removable internal supporting part showing the spaces between radial projections for the passage of the cooling fluid.

Referring now particularly to Fig. 1, 10 is a main socket member preferably formed of insulating or plastic material and having a large recess 11. In the upper part of the recess 11, there is imbedded a metal ring 12 having screw threads thereon to which is attached a clamping screw 13 having a threaded metal ring 14, adapted for engagement with the ring 12. Extending from the bottom of the recess 11 is a metal tube 16 through which cooling water is conducted to the recess. This cooling fluid tube 16 is imbedded in the plastic and over a considerable part of the same there extends a plastic skirt portion 17. The upper end of the tube 16 is offset at 18 and has internal threads 19. Connected to the threads 19 and extending into the recess is a lamp support 21 of spider cross-section and having radially-extending portions 22. Between the portions 22 are passages 23, Fig. 4, for conducting

the cooling water along the support 21. The bottom of the recess 11 has a conical formation 24 in which is fixed a metal sleeve 25 through which the support 21 extends for connection with the threads 19 of the offset tube end 18. This sleeve 25 provides a metal lining for a central opening 26 within the conical portion 24. To the end of the conical portion 24 there is fastened a transparent sleeve 27 adapted to extend outwardly along the lamp support 21 and lamp to a point near the outer end of the lamp. In order to provide a good sealing engagement of the transparent tube 27 with the conical portion 24, there is provided a sleeve 28 of rubber. Tube 27 is flared outwardly as indicated at 29 to nicely receive the rubber and to provide a flange against which the inner end of an internal connecting part 31 may cooperate to secure the rubber in sealing engagement with the cooperating parts. Metal sleeve 25 extends upwardly above the conical portion 24 and prevents rubber gasket 28 from expanding inwardly between arms of the spider so as to hamper the water flow.

This connecting part 31 has a central opening 32 extending throughout its entire length and which is flared at the bottom as indicated at 33 to fit upon the conical portion 24. The connecting member extends for the full height of the recess and the transparent sleeve 27 is contained within its opening 32.

The lamp support 21 has its outer end cut out as indicated at 34, Fig. 3, to receive a lamp 35. This lamp 35 has its lower terminal 36 fitted within the recess 34 of the support 21 to make tight contact with the support. Surrounding the recess 34 of the support 21 are finger projections or prongs 37 which are adapted to spring slightly as the lamp 35 is pushed into the support.

The lamp 35 has a terminal 38 at its opposite end adapted to be seated in a rubber member 39 carried within the reduced end of a transparent outer casing 41 adapted to cover the lamp and be spaced from the internal transparent sleeve 27.

The connecting member 31 is also of plastic material and has a ledge 42 on which is rested a ring 43 of metal or other material. At the inner periphery of the ring 43, the ring material is thickened to provide a crown 44 for supporting one end of a rubber sealing ring 45.

The lower end of the outer casing 41 is flared at 46 and rests in the rubber sealing ring 45. In order to provide a good distribution of the rubber ring 45 against the outer wall surface of the flared end 46 and in recess 11 and to make a positive seal, there is provided a pressure ring 47 shaped to force the rubber about the flared end of the casing 41 and against walls of the main socket 10. The internal diameter of the outer casing is slightly larger than the connecting member 31 so as to provide a space 48 through which cooling water being returned to an outlet pipe 49 may pass. The ring 47 is forced into the rubber 45 by the clamping screw 13.

The connecting member 31 has radially-extending projections 55, Fig. 5, spaced circumferentially about its main portion 56 to provide cooling fluid passages 57. These passages 57 communicate with an annular recess 58 from which the cooling pipe 49 leads. The cooling pipe 49 extends through a plastic skirt portion 59.

The metal tubes 16 and 49 extend below their skirt portions, and hose connections 61 and 62 fit over the tubes 16, 49, and the skirt portions 17, 59.

Water enters the holder through the tube 16

and passes the passages 23 of the lamp support 29 and the inner sleeve 27. This water on leaving passages 23 surrounds the vapor lamp 35 to cool the same. Cooling fluid leaving the outer end of the sleeve 27 will circulate about the terminal end 39 of the lamp to cool those portions thereof. The cooling fluid then reverses its direction of flow and passes between the outer casing and the sleeve 27, space 48, passages 57 in the connecting member 31, annular space 58 to exit tube 49. This path can be traced by the arrows.

The hose connections 61 and 62 may connect as shown in Fig. 2 with inlet and outlet conduits 64 and 65. About the respective conduits 64 and 65 are collar terminals 66 and 67 having the wires 66a and 67a leading from any electrical source not shown.

In order to establish electrical connection 20 through the hose connections 61 and 62, there are provided extensible wires 70 having fastening clips 71 adapted to be snapped over diametrically-extending terminal pins 72 in the conducting tubes 16, 49, 64, 65. When the hose connections 25 61 and 62 are slid or pulled off from the cooling pipes the fastening clips 71 are exposed and can then readily be detached from the pins 72.

The terminal 38 of the vapor lamp is connected through a contact ring 75 and a lead 76 extends 30 through space between the outer casing 41 and the sleeve 27, recesses 57 and annular space 58 in the connecting member for connection with the upper end of the metal cooling tube 49.

A reflector 77 may be fitted by its sleeve portion 35 78 to the holder 10.

It should now be apparent that there has been provided a holder for vapor lamps adapted to be cooled, which is of simple construction easily assembled and disassembled and efficient in operation.

It will also be apparent that all the electrical and water connections are established at but one end of the jacket, thereby to provide for an easy mounting of the lamp holder, and that the glass tubes are of simple design and economically produced.

The shape of the glass tubes is such as to permit easy grinding in case extreme accuracy in mounting the parts is desired. Cooling fluid need not be water, but may be of some other medium, such as air, provided the outlet connection is made bigger and adequate pressure-resisting tubes are used. All parts subject to power are fully and sufficiently shielded and insulated as 50 to permit handling of the unit with bare hands during the operation. Also, the plain glass tubes may be replaced with other tubes of colored or filtered glass or of other insulating and transparent material. Also, the standard tubes shown 55 60 may be replaced with other ones which are longer or of different shape for use in cases where the light source must be at a considerable distance from the reflector casing.

I have described what I believe to be the best 65 embodiments of my invention. I do not wish, however, to be confined to the embodiments shown, but what I desire to cover by Letters Patent is set forth in the appended claims.

I claim:

70 1. In combination, a lamp holder having an enlarged recess, cooling pipes communicating respectively with the recess, a lamp support secured in the bottom of the recess and providing for passages for cooling fluid entering the recess

by way of the pipe connected with the bottom

thereof, a lamp fitted in the upper end of the lamp support, a transparent sleeve surrounding the lamp support and the lamp having its inner wall spaced therefrom to provide a passage for the cooling fluid moving through the support, a connecting member surrounding the transparent sleeve for securing the same to the bottom of the recess, an outer casing surrounding the lamp and the inner sleeve and having its wall spaced therefrom to provide a return passage for the 10 cooling fluid, said connecting member having passages for conducting the fluid from the inner end of the casing to an outlet cooling pipe in the holder, and clamping means for securing the outer casing to the connecting member and to the holder.

2. In combination, a main holder having an enlarged recess therein, inlet and outlet cooling pipes respectively communicating with the recess, a lamp support mounted in the recess and having passage means for conducting cooling fluid therethrough, said recess having a vertically-extending conical portion surrounding a part of the lamp support, a lamp mounted on the outer end of said support, a transparent sleeve surrounding the support and the lamp and having its inner end resting on the top of the conical portion, a connecting member cooperating with the inner end of the transparent sleeve for fixing the sleeve to the conical portion, said connecting member further having a tapering recess in its inner end adapted to cooperate with the conical portion, an outer casing surrounding the inner sleeve and lamp secured in the outer end of the recess and against the connecting member, said connecting member having passages therein for receiving cooling fluid leaving the outer casing and conducting the same to an outlet cooling pipe.

3. In combination a holder having an enlarged recess, cooling pipes communicating respectively with the recess, a lamp support extending upwardly from the bottom of the recess, a lamp mounted in the lamp support, a transparent sleeve surrounding the lamp support and lamp for conducting a cooling fluid over the lamp, said transparent sleeve being flared at its inner end, rubbing sealing means surrounding the flared end of the sleeve, a connecting member surrounding the sleeve and the rubber sealing means and adapted to engage the bottom of the recess, an outer casing surrounding the sleeve and the con- 45

necting member and having a bottom flared end, a rubber sealing means surrounding the bottom flared end of the outer casing, clamping screw means surrounding the outer casing and forcing the flared bottom end of the casing inwardly against the connecting member, and passage means in the connecting member for conducting fluid between the outer casing and the outlet pipe.

4. In combination, a holder having a large recess, inlet and outlet cooling pipes in the holder, a lamp support mounted in the recess and extending outwardly toward the open end thereof, said lamp support constituting an electrical conductor, a lamp connected to the outer end of the support to receive current therefrom, a transparent sleeve surrounding the lamp and support, a connecting member about the sleeve and seated in the bottom of the recess, an outer casing surrounding the connecting member, a clamping nut for securing the outer casing to the connecting member and to the holder, a terminal connection extending from the outer end of the lamp between the casing and the transparent sleeve and through the connecting member for connecting with one of the cooling pipes, and means for conducting fluid between the sleeve and the lamp and between the outer casing and the sleeve and through the connecting member to the outlet pipe.

5. The invention as defined in claim 4 in which the outer casing has a rubber element for receiving the outer terminal of the vapor lamp, and a rubber cushioning means between the respective inner ends of the internal transparent sleeve and the outer casing whereby a fragile transparent material of the inner sleeve and the outer casing will have a rubber connection with the holder and connecting member.
